UNITED STATES PATENT OFFICE.

FRED L. DAGGETT, OF SOMERVILLE, MASSACHUSETTS.

DESIGN FOR A CANDY-BOX.

SPECIFICATION forming part of Design No. 36,436, dated July 14, 1903.

Application filed June 1, 1903. Serial No. 159,521. Term of patent 14 years.

To all whom it may concern:

Be it known that I, FRED L. DAGGETT, a citizen of the United States, residing at Somerville, county of Middlesex, and State of Massachusetts, have invented a new, original, and ornamental Design for a Candy-Box, of which the following is a specification, reference being had to the accompanying drawing, forming a part hereof.

The figure in the drawing shows the box in perspective.

Having described my invention, what I claim as new, and desire to secure by Letters Patent of the United States, is—

The ornamental design for a candy-box substantially as herein shown.

FRED L. DAGGETT.
